UNITED STATES PATENT OFFICE.

EMILE BACHELET, OF NEW YORK, N. Y.

ELECTROMAGNETIC SOUND-WAVE THERAPEUTIC APPARATUS.

1,001,236.

Specification of Letters Patent. Patented Aug. 22, 1911.

Application filed August 7, 1908. Serial No. 447,449.

To all whom it may concern.

Be it known that I, EMILE BACHELET, of New York, in the county of New York and State of New York, have invented certain new and useful Improvements in Electromagnetic Sound-Wave Therapeutic Apparatus; and I hereby declare that the following is a full, clear, and exact description thereof, reference being had to the accompanying drawings, which form part of this specification.

This invention is a novel apparatus for treating diseases of the ear, catarrh of the head, neuralgia, and other ailments to which the delicate organs of the human head are subject, and its object is to provide an apparatus whereby the portion of the head affected and in particular the aural passages can be treated simultaneously by magnetic and sound waves.

To this end the invention consists in a novel apparatus which I term an electromagnetic and sound wave therapeutic apparatus, whereby magnetic impulses or lines of force and sound waves or vibrations may be simultaneously generated and the intensity of each and both of these can be varied or regulated to suit the condition of the patient and produce the best results.

In the accompanying drawings I have illustrated a form of such apparatus embodying the invention and especially designed for use in treating severe cases of deafness, and I will now describe the invention in connection with said drawings, so that others skilled in the art will be able to comprehend and use the same.

In said drawings: Figure 1 is a side view of a complete therapeutic apparatus embodying the invention and showing two magnetic and sound wave generators arranged in series. Fig. 2, is an enlarged vertical central longitudinal section through one of the said generators, Fig. 3, is a section on line 3-3 Fig. 2; and, Fig. 4, is a sectional view of a slight modification.

Each generator comprises a preferably cylindric casing 1, which may be closed at the front end by a cap 1^a, and at the rear end by a cap plate 1^b, which cap plate may be connected to the cylinder by a threaded joint, as indicated in Fig. 2. Suspended within the casing is a solenoid 2, which is centered therein by means of insulating blocks 2^a, attached to the casing by screws, or in other suitable manner, as indicated in

the drawings, and preferably so as to leave an air gap *a*, between the outer wall of the solenoid and the inner wall of the casing, for a purpose hereinafter explained. Within the solenoid is a metallic core 2^b, which may be fixed but is preferably adjustable as hereinafter explained. The terminals of the solenoid 2 are connected to the binding posts 2^x, 2^y, respectively, as indicated in the drawings, which binding posts may be connected by wires to any suitable source of electricity. The solenoid should be energized by an intermittent or alternating current, and consequently if a battery or direct current generator is used as a source of electrical supply, an interrupter, not shown, should be placed between the battery and the wave generators.

The core 2^b, as shown in Fig. 2, may be adjusted by means of screw 3, extending through the cap plate 1^b, and engaging a threaded aperture in the core, and by rotating screw 3, the core can be shifted longitudinally in the solenoid. When the solenoid is energized by an intermittent alternating current magnetic waves are generated and thrown off at the poles of the solenoid, and particularly at the ends of the core 2^b such waves being graphically indicated by the dotted lines in Fig. 1. In this connection I observe that when two generators are employed, as indicated in Fig. 1, they should be connected in series so that the south pole of one solenoid or core is directly opposed to the north pole of the other solenoid or core, with the result that the solenoids or magnets act in unison and create the strongest magnetic field in central line between the generators.

At the rear side of the solenoid opposite the opening 1^c, adjacent plate 1^b, I place a metallic diaphragm 3, which serves as a sound wave generator and also to concentrate or enhance the strength of the magnetic field between the magnets. Acting as a sound wave generator the diaphragm will be attracted more or less when the core is energized, and will thus vibrate and produce sound waves, which can pass freely through the air gap *a*, and out through an opening 1^c in the front plate 1^b, directly opposite the end of the core 2^b, so that the sound waves can freely escape from the generator and will directly enter the ear of the patient.

A thumb screw 4 is tapped through the

plate 1^b, and has a disk 4^a on its inner end which may be adjusted into contact with the diaphragm 3, and by adjusting said screw the diaphragm can be forced nearer to the 5 coil. This disk 4^a might be faced with rubber, as shown at 4^b in Fig. 4, for the purpose of avoiding metallic contact between the diaphragm and the disk. As a convenient 10 means of assembling the parts the screw 3 is shown as tapped through the screw 4.

Fig. 1, shows the apparatus in use for treating patients in severe cases, but in very mild cases, or in treating only one ear, one of the generators might be dispensed with.

15 The principle under which the apparatus is operated is that a magnetic wave is produced each time the current is varied or broken and each wave will pass through the ear and head simultaneously with the entry 20 of the sound wave produced by the vibrating diaphragm, which latter is actuated by the current passing through the solenoid, which current magnetizes the core which in turn attracts and vibrates the diaphragm at the 25 same speed as the vibrating current.

The thumb screw 3, is used to regulate the intensity of the magnetic field; by adjusting the same the core may be moved away from the diaphragm with the result 30 that the magnetic waves are very much strengthened as the pole of the core is brought nearer to the opening 1^c, but the pitch or intensity of the sound waves are decreased; but if the core is moved toward the 35 diaphragm the sound waves will be increased. By means of screw 4, the diaphragm can be made to partially follow up the core.

The solenoid is preferably wound with 40 coarse wire to prevent heating.

In cases where the sound waves are not required or desired the diaphragm 3, might be removed by unscrewing plate 1^b.

When the apparatus shown in Fig. 1, is 45 used with the generators in series a large number of the magnetic lines of force will be directly attracted through the head from one magnetic generator to the other by reason of the opposite polarity of the opposed 50 poles of the magnets.

The manner in which the adjustment of the cores will vary the field between the two magnets, is thought to be as follows: While the adjustment of the cores toward each 55 other will not decrease the reluctance of the magnetic circuit comprising the two cores and the two diaphragms, said adjustment will increase the reluctance of the local magnetic circuit, comprising one core and dia-

phragm as the air gap between the core and 60 diaphragm is increased. Hence the local or stray field will be decreased and the main field will be increased, as obviously the strength of the field between the two magnets, or the main or useful field, will depend 65 upon the strength or intensity of the leakage or stray field.

The core is preferably made of soft iron and might be permanently fixed, as indicated in Fig. 4. This would keep the magnetic field normal, but the sound waves would be controlled by the screw 4, bringing the disk 4^a more or less forcibly into contact with the diaphragm.

In my scientific experiments I have found 75 that the sound waves are greatly enhanced in value as a therapeutic agent by the assistance or coöperation of a heavy magnetic wave.

Instead of making the casing entirely of 80 hard rubber, as indicated in Figs. 1 to 3, I might make the cylindrical shell and rear plate of metal, as indicated in Fig. 4, leaving the front plate of rubber.

When two co-acting generators are used 85 in tandem, as indicated in Fig. 1 they are placed against the ears of the patient and held in position by any convenient means, as by a connecting spring band conventionally indicated at 6 in the drawing and which may 90 be of any desired or suitable kind and placed over or back of the head or in any position most convenient and comfortable to the patient. When treating but one ear one generator could be detached; or a single 95 generator attached to a holder of any suitable kind could be employed.

Having thus described my invention, I claim:

In an electro-magnetic therapeutic apparatus; the combination of a pair of opposed generators, each comprising a casing having an opening in one end, a solenoid centered in said casing in axial alinement therewith, a core in the solenoid, a diaphragm in 105 the casing at the end of the solenoid opposite the opening in the casing, a screw for regulating the diaphragm, and a screw for adjusting the core, the latter screw being tapped through the former.

110 In testimony that I claim the foregoing as my own, I affix my signature in presence of two witnesses,

EMILE BACHELET.
